FINE GOLD SAVING MACHINE

George B. McKeever, Seattle, Wash.

Application August 25, 1936, Serial No. 97,836

1 Claim. (Cl. 209—44)

My present invention relates to the general art of concentrators as relates to placer mining, and the like, and more particularly to a fine gold saving machine.

One of the perplexing problems that has always confronted miners is the recovery of fine gold of the type often referred to as "flour gold." In this form gold is easily carried by water and particularly so by dirty water, as is encountered in placer mining. The reason for this tendency is that as the gold particles become very small their ratio of exposed surface to their weight becomes very high; consequently concentrators, sluice boxes, and other recovery devices that operate on the premise that heavy material always sinks, do not normally collect the very fine gold. This has been proved in almost every placer gold producing field. It has often been found that by carefully working over the tailings of early operations a large percentage of gold still remains in the ground. Many attempts have been made to produce equipment for the recovery of this fine gold but those observed have been characterized by their initial high cost and high cost of operation with no surety of complete recovery of the flour gold. In my present machine I have provided equipment which is light in weight, can be easily transported, and so simple in its structure that even those of limited means can secure and operate it.

The success of operation resides in the peculiar construction of my machine which causes the gold bearing water to pass through woven material, preferably cocoa-matting, and to be thus well spread out in a shallow stream, so that there is no great mass of water for the gold to settle down through. Normally, my present machine is intended to serve principally as a collector or concentrator, and as no amalgum is used, coated particles of gold are saved with the same ease as clean gold.

It has been observed that moss overhanging a gold bearing stream acts as a fine gold collector; the small particles being arrested by contact with the moss fibres. In my machine I substitute cocoa-matting as a commercial equivalent of the moss and find it serves in the same manner.

A further object of my present invention is to supply operating means for my equipment so arranged that a single source of power, driving a water pump at or near the water's edge, provides the entire motive energy required in my equipment. The water may be, of course, supplied under pressure to my machine by any suitable means, as for instance static head, and it not

only operates the vibrating mechanism but is divided to form several streams as it passes into my machine so as to assure the proper functioning during each stage of the separation.

Other and more specific objects will be apparent from the following description taken in connection with the accompanying drawings, wherein

Figure 1 is a side elevation of my separator and riffle. 10

Figure 2 is a fragmentary view showing a modified construction of my riffle that is normally best used where sand only is handled through the machine.

Figure 3 is a fragmentary, vertical, sectional view through a typical riffle employed in my machine. 15

Figure 4 is a perspective view showing the agitator and separator of my device with the rocker screen removed, and with certain other parts broken away to better illustrate the construction. 20

Figure 5 is a perspective view of the rocker screen used in my device.

Figure 6 is a perspective view showing the upper riffle of my device, the same being broken away to better illustrate the construction. 25

Figure 7 is a perspective view showing the lower cocoa-mat riffle used with my device, the same being shown partly broken away.

Figure 8 is a perspective view of the transfer spout leading from the upper riffle to the lower flume. 30

Figure 9 is a vertical, sectional view through the agitator of my device showing the rocker screen and other parts in section. 35

Figure 10 is a fragmentary view, showing in a vertical section, the upper and lower riffles.

Figure 11 shows the extreme right hand end of Figure 10 together with a transfer spout and lower flume. 40

Figure 12 is a view, similar in part to Figure 1, but with the shaker, or agitator, mechanism substantially enlarged to better illustrate certain features of construction.

Figure 13 is a side elevation similar to Figure 12 with certain parts broken away to better illustrate their construction. 45

Referring to the drawings, throughout which like reference characters indicate like parts, 14 designates, in general, my agitating, or shaking, 50 device. This consists of a suitable frame having a plurality of vertical posts as 16, 17, and 18 which are shown at their upper limits with suitable cross members which, in turn, support the upper water distributor 20. Pivotedly secured 55

to the upper end of upright 16, are the rocker links 21 and 22 which, in turn, are pivotally secured to the frame of rocker screen 24. This frame work supports a screen 25, preferably 5 made of metal, and is in turn supported at its rear, or lower, end by roller hangers 26 and 27. The rollers of these hangers are guided by the two side members of each hanger so as to bear on adjustable bearing members 28, the adjustment being provided so that the bearing surface 10 may be maintained in a level or horizontal plane so that no undue load will be placed upon the shaking mechanism, for screen 25.

Suitable baffles as 30 and 31 are provided above 15 screen 25 so that the gravel will be more evenly distributed thereon and will come directly under water projected from holes 32 in the water distributor 20.

The shaking or vibration is provided by the 20 connecting rod 34 which engages crank 35. This crank is suitably connected as by the reduction gear means 36 and 37, to a water driven impeller 38.

Water for the operation of my device is supplied by the supply pipe or hose 40. This may 25 be furnished from any suitable source of water under pressure as for instance a hydrostatic head, or from a motor, engine, or driven pump. As the water supply is led up to the machine it 30 is first brought under control by valve 41 which is capable of diverting all, or a portion, of the same directly out onto the ground or, at the will of the operator, pass all, or any portion, of the water desired up through pipe 42 into the 35 machine proper.

The water passing up pipe 42 is divided first 40 into a stream to feed the impeller nozzle, or jet, 43. This water when used in driving the impeller is fed down through the return pipe 44 into the lower trays 45 where it serves to wash downwardly any sand, fine gold, or other material 45 passing upwardly through hose 47 into the upper water distributor 20. Here the water enters an enlarged chamber having a reduced opening, or jet, 48 at its lower end. This serves to restrict the water flow and to provide a uniform discharge throughout the various holes 32. This water so discharged through holes 32 serves to wash the gravel, or sand, as it is thrown into the machine onto baffles 30 and 31 and continues 50 to wash the same as it lies on screen 25. The remainder of the water is discharged from jet 48 and washes the coarser material which is passed on over screen 25 into the upper riffles 50.

Disposed below in a position to receive the discharge from tray 45 is the lower riffle 52. This riffle is so placed as to receive the fine material which is passed through screen 25 into tray 45 and then, due to the action of water passing 55 through pipe 44, is washed down onto the cocoa-matting screen 53 which extends substantially the full length of the lower riffle. Under certain conditions this lower riffle may be modified after the showings of Figure 2 in which the riffle is expanded transversely so as to give a wider stream. This is particularly desirable where clean sand is being run through the machine. Here it is found desirable to have a plurality of guides or deflecting baffles 54 so as to distribute the material substantially evenly over 60 the cocoa-matting. This matting is supported by a plurality of closely spaced rods 55 extending from one side to the other of the lower riffle box. It is held in place by an equal number of smaller rods 56 disposed alternately with rods 55, par-

ticularly after the showing of Figure 10. The spacing of these rods should be such that there will be no tendency for the cocoa-matting to sag under the weight of material dumped on it, and to be, further, so arranged that it will be suspended above the bottom 57 of box 52 so that a shallow stream of water, part of that discharged out of box 45, can pass entirely through the cocoa-matting and out underneath the same where it will be discharged into the lower flume 10 60.

Method of operation

In operating my fine gold saving machine the gold bearing gravel, sand, or pulp, is deposited by 15 any convenient means into the hopper formed by baffle boards 30 and 31 so that it comes under the action of water jets from holes 32. Here the material is washed and the finer material is thus washed through screen 25 into the lower tray 45. The coarser material, due to the longitudinal vibration, or shaking, of screen 25, by action of 20 crank 35, passes the heavier materials, gravel, large pieces of rock and the like on into the upper riffle box 50, where a plurality of arresting riffles, 62, of the usual construction are provided. 25

The sand, fine materials, and particularly the "flour gold", or "float gold" as it is sometimes termed, is washed out of tray 45 onto the top of the cocoa-matting 53 of riffle 52. Here the sand and water pass over the matting in a shallow stream with a small portion of the water filtering through the matting leaving the fine gold in it. The space under the matting is sealed so that the moving water creates a suction that draws the gold bearing water through. This arrangement keeps the gold wet thus destroying molecular cohesion that normally tends to float the gold, just as a needle will float on water. Sand partially fills the space in the matting adding to the suction below the matting. 40

This action brings about the condition similar to moss or grass roots in water which is known to arrest the movement of fine gold in streams.

The action of the cocoa-matting is believed to be a very important one as the water carrying the fine gold passes through the upstanding fibres of the matting, or it actually comes through it into very intimate contact with the fibre material, which has the faculty of retaining the tiny flakes of gold while permitting the water, 50 due to the draft suction, or molecular cohesion, to be drawn through the matting and be discharged. 45

The coarser gold and coarser concentrates which accumulate in riffle 62 may be handled in 55 any of the ordinary ways well known to users of this type of equipment. The fine gold caught on the matting 53 is removed normally by washing the same in a tray or bath, however, after the matting material has been in use for some time it is desirable then to burn the matting in a metal tray and recover the fine gold from it. 60

The foregoing description and the accompanying drawings are believed to clearly disclose a preferred embodiment of my invention but it will be understood that this disclosure is merely illustrative and that such changes in the invention may be made as are fairly within the scope and spirit of the following claim. 65

I claim:

A hydraulic mineral separator having a stream of water under pressure, a reciprocable shaker screen, a hopper above the screen, a sluice-way under the screen, a riffle adjoining said sluice-way, a water motor operably connected with said 75

screen to reciprocate the same, means for conveying the stream under pressure to said motor, a conduit diverting the portion of said stream passing through said motor to wash over said 5 sluice-way, a conduit conveying the other portion of said stream to a perforated distributing

tank over said hopper and adapted to spray water over the hopper, and a nozzle on the free end of said latter conduit to direct the remaining stream of water over said riffle.

GEORGE B. McKEEVER.
